UNITED STATES PATENT OFFICE.

JOHN J. GRUENIG, OF MILES CITY, MONTANA.

SOLE-Straightening Means.

1,135,106.

Specification of Letters Patent. Patented Apr. 13, 1915.

Application filed December 24, 1914. Serial No. 878,942

To all whom it may concern:

Be it known that I, JOHN J. GRUENIG, a citizen of the United States, residing at Miles City, in the county of Custer and State of Montana, have invented certain new and useful Improvements in Sole-Straightening Means, of which the following is a specification.

The present invention relates to a device 10 adapted to be applied to the soles of shoes for the purpose of holding the same in a perfectly flat position and preventing the toes of the shoes from curling upward and getting out of shape when not in use, the 15 object of the invention being to provide a device of this character which embodies novel features of construction whereby it can be quickly applied to a shoe without injury to the same and operates effectively 20 to prevent deformation of the shoe such as results from curling or bending of the sole.

A further object of the invention is to provide a shoe sole straightening device which is inexpensive in its construction, 25 which can be instantly adjusted to fit any size of shoe, which will not injure or mar the shoe, and which will hold the sole of the shoe in a perfectly flat position so as to prevent the toe from curling upward.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a side elevation of a shoe sole straightener constructed in accordance with the invention, showing the same as applied to a shoe. Fig. 2 is a top plan view of the same with the shoe removed. Fig. 3 is a side elevation of the shoe sole straightener, the clamping lever being indicated by dotted lines in the position assumed when sprung upwardly preparatory to moving the same into inoperative position, and by full lines as swung into inoperative position. Fig. 4 is an enlarged detail perspective view of the clamping lever and heel clamping bar. Fig. 5 is a similar view of the slide upon which the clamping lever is mounted. Corresponding and like parts are referred to in the following description and indicated in all the views of the drawing by the same reference characters.

Specifically describing the present embodiment of the invention, the numeral 1 designates the main frame of the device which is designed to extend longitudinally under the shoe and is provided at one end thereof with a returned portion providing a clip adapted to engage the toe portion of the shoe sole, the opposite end of the main frame or stock being shown as formed with a suitable handle 2, as well as an eye 3 by means of which the device may be hung upon a nail or the like and suspended against a vertical support. The main frame 1 may be formed from a single length of wire and preferably includes a pair of spaced and parallel side bars 1^a of a sufficient length to extend entirely under the full length of the shoe. The toe clip mentioned above may comprise a cross bar 4 connecting outwardly and upwardly returned ends 1^b of the side bars 1^a. This cross bar is adapted to fit over the projecting portion of the sole at the toe of the shoe and may have an intermediate portion thereof slightly flattened, as indicated at 5, to provide a tooth like member such as will positively engage the edge of the sole without danger of slipping.

A slide 6 is mounted upon the side bars 1^a of the main frame so as to move back and forth thereon. This slide 6 may be formed from a length of wire which has opposite ends thereof coiled to provide sleeves 7 which receive the respective side bars 1^a of the frame and are slidable thereon. A spring clamping lever 8 is pivotally mounted upon the slide 6, one end thereof having a transversely disposed locking bar 9 swiveled thereon, while the opposite end thereof is bifurcated to provide spaced arms 8^a which support a yieldably mounted heel clamping bar 10. As indicated upon the drawing, the clamping lever and heel clamping bar may be formed from a single length of wire which is looped and suitably bent to provide the heel clamping bar 10 and bifurcated end of the lever and then has the ends thereof twisted together to form the locking end of the lever. The wire is coiled at the base of the bifurcated end of the lever to provide the pivot eyes 11 which loosely receive the transverse bar of the slide 6. It will also be observed that the wire is coiled at opposite ends of the heel clamping bar 10, as indicated at 12, to provide a yieldable mounting

for the said bar 10. If desired, an intermediate portion of the bar 10 may be flattened at 13 to provide a tooth like member for biting into and firmly engaging the heel 5 of the shoe. By reference to Figs. 1 and 3 it will be observed that the heel clamping bar 10 is offset upwardly from the plane of the bifurcated end 8^a of the clamping lever so that the looped portions 12 of the wire 10 are enabled to act as coil springs to hold the heel clamping bar yieldably in operative position.

The transverse locking bar 9 is swiveled at 14 upon the extremity of the clamping lever 8 and is of a sufficient length to project over and engage the side bars 1^a of the main frame when in operative position, as indicated by Figs. 1 and 2. However, when it is desired to release the shoe or adjust 20 the device the lever 8 is sprung upwardly, as indicated by dotted lines on Fig. 3, and the transverse locking bar 9 swung into an upright position so that it no longer engages the side bars 1^a but can be swung 25 downwardly between the same, thereby admitting of the clamping lever being moved into inoperative position, as indicated by full lines upon Fig. 3, when the clamping lever is in this position the shoe may be 30 readily placed in proper position upon the frame 1 or removed therefrom, and the slide 6 moved back and forth upon the side bars 1^a to adjust the device to a shoe of any length. In Fig. 1 the device is shown as 35 applied to a shoe 15, the projecting end of the sole 16 at the toe of the shoe being engaged by the toe clip 4, while the heel 17 of the shoe is engaged by the heel clamping bar 10. The sole 16 of the shoe is held in an 40 absolutely flat position against the main frame 1 so that there is no danger of the shoe becoming deformed by reason of any tendency of the sole 16 to curl upwardly. The bifurcated end 8^a of the clamping lever 45 is sufficiently wide to engage the side bars of the frame and coöperate with the transverse locking bar 9, when the latter is in operative position, to maintain the operating lever 8 under a slight tension and thereby cause the 50 sleeves 7 of the slide 6 to frictionally engage the side bars 1^a and lock the slide in an adjusted position. However, by springing the clamping lever 8 upwardly and then turning the locking bar 9 into an upright position, as indicated by dotted lines on Fig. 3, the clamping lever can be swung downwardly into an inoperative position, as indicated by full lines on the said figure, and the slide 6 then moved back and forth upon 55 the side bars 1 as may be required to adjust the device to any particular size of shoe.

Having thus described the invention, what I claim as new and desire to secure by Letters Patent, is:—

65 1. A shoe sole straightening device in-

cluding a flat frame arranged to fit under the sole of a shoe, toe engaging means upon the frame, a slide mounted upon the frame, a clamping lever mounted upon the slide, heel clamping means carried by the clamping lever, and locking means for holding the clamping lever in operative position.

2. A shoe sole straightening device including a flat frame arranged to fit under the sole of a shoe, toe engaging means upon the frame, a slide mounted upon the frame, a clamping lever mounted upon the slide, a heel clamping bar carried by the clamping lever, a yieldable mounting for the heel clamping bar, and locking means for holding the clamping lever in operative position, the movements of the slide upon the main frame admitting of the position of the heel clamping bar being adjusted for engagement with various sizes of shoes.

3. A shoe sole straightening device including a flat frame arranged to fit under the sole of a shoe and formed with spaced side bars, toe engaging means upon the frame, a slide connecting the spaced side 90 bars of the frame and mounted thereon, a clamping lever pivotally mounted upon the slide at an intermediate point in its length, heel engaging means at one end of the clamping lever, and a transverse locking bar 95 loosely connected to the opposite end of the clamping lever, said locking bar being adapted to extend across and fit against the side bars of the main frame to hold the clamping bar in operative position or to 100 be turned into an upright position so as to swing between the side bars of the frame and admit of the clamping lever being swung into inoperative position.

4. A shoe sole straightening device including a flat frame arranged to fit under the sole of a shoe and formed with spaced side bars, toe engaging means upon the frame, a slide connecting the side bars and formed with guide sleeves loosely engaging 110 the same, a spring clamping lever pivotally mounted upon the slide at an intermediate point in its length, a heel clamping bar carried by one end of the clamping lever, and a transverse locking bar swiveled upon the 115 opposite end of the clamping lever, said locking bar being arranged to extend across and rest upon the side bars of the frame to hold the clamping lever in operative position or to be swung into an upright position 120 so as to clear the side bars when the clamping lever is swung into inoperative position.

5. A shoe sole straightening device including a flat frame arranged to fit under the sole of a shoe and formed with spaced side bars, toe engaging means upon the frame, a slide connecting the side bars and mounted thereon, a spring lever pivotally mounted at an intermediate point in its 125 length upon the slide, one end of the lever 130

being bifurcated, a heel engaging bar carried by the bifurcated arms of the lever, a yieldable mounting for the heel engaging bar, and a transverse locking bar swiveled 5 upon the opposite end of the lever and arranged to extend across and rest upon the side bars of the frame to hold the lever in operative position or to be swung into an upright position so as to clear the said side 10 bars when the lever is swung into an inoperative position, the back and forth move-

ment of the slide upon the side bars admitting of the lever being adjusted for proper engagement of the heel engaging bar with various sizes of shoes.
